Attorney

UNITED STATES PATENT OFFICE.

CHARLES EDMUND PALMER, OF CASTLE CARY, ENGLAND.

OIL-LAMP.

1,218,889.

Specification of Letters Patent. Patented Mar. 13, 1917.

Application filed August 18, 1916. Serial No. 115,731.

To all whom it may concern:

Be it known that I, CHARLES EDMUND PALMER, a subject of the King of Great Britain, and residing at Castle Cary, in the county of Somerset, England, railway lampman, have invented certain new and useful Improvements in Oil-Lamps, of which the following is a specification.

This invention relates to oil lamps of the type in which, as has been proposed, different portions of a wick may be brought in succession beneath the flame opening, whereby the wick will last for a long while without need for being trimmed, and whereby if the movement of the wick is rendered automatic the lamp will burn for a long period continuously without requiring any attention. According to means which have previously been proposed for the purpose, the wick was to be drawn over a rigid support and the portion of the wick which was at any time beneath the flame opening would be some part of the wick intermediate its ends, or the wick was formed as a ring which was clamped between sides of a revolving holder and portions of the surface of this ring were brought in succession beneath the wick flame by the revolving movement of the holder and the ring was fed with oil by a pillar of wick material which dipped into the oil and made contact at its upper end with the ring.

Now, this invention has for its main object to utilize a wick of flat shape of which the surface of the upper end only will move beneath the flame opening and bring different portions thereof in succession beneath such opening.

According to this invention, a flat wick is employed which passes up through a correspondingly-shaped holder and is of considerably greater width than the flame opening through the flame controller (the width of the opening being regarded as the distance between its ends), and the upper surface of this wick is moved edgewise beneath the flame opening either automatically by means of a float within the oil reservoir, or, if desired, from time to time by hand.

A convenient practical application of the invention is illustrated by the drawings herewith, of which—

Figure 1 shows, partly in side elevation and partly in section, as much as is necessary in this view to illustrate the lamp.

Fig. 2 is a plan view of the burner appa-

ratus shown as detached from the reservoir or lamp base.

Fig. 3 is a vertical section through the burner apparatus taken on the line *x x* of Fig. 1, the lower portion of the wick-holder being broken away for convenience of illustration; and,

Figure 4 shows a side elevation, partly in section, of a modified form of the burner apparatus.

Referring first to the application of the invention shown by Figs. 1, 2, and 3:—A is the oil reservoir, B the wick-holder which is capable of turning about a fixed axis *b* which is carried by the reservoir. C is a pair of arms which are fixed at their inner ends to the lower end of the wick-holder B, and have pivoted between their outer ends a float D which may be of hollow sheet metal structure or of other convenient construction. G is a hood or flame-controller which is struck to a curve from the axis *b* as a center and passes over the entire path through which the upper end of the wick, which is also struck to a curve from the same center, moves as it is tilted from the one extreme position shown by full lines, Fig. 1, due to the reservoir being full, to the other extreme position shown by broken lines, Fig. 1, due to the reservoir being substantially empty. Through the middle of this hood is formed a flame-opening *g* which is of a length which adapts it for the required flame. When the wick-holder is in the position shown by full lines, Fig. 1, a short length only of the upper end of the wick, measured from the leading end, is beneath this opening, and the remaining portion of the upper end of the wick is for the time inert.

As the oil in the reservoir gradually lowers, the upper end of the wick gradually moves over toward the position shown by broken lines, Fig. 1, the leading end of the wick passing from under the opening and becoming inert while other portions of the wick come gradually under the opening, and thus the wick may be used without need for trimming while substantially the whole of the oil within the reservoir is being consumed.

The main body or straight portion of the wick-holder B is carried up to within a short distance of the under surface of the hood G, as clearly shown by Fig. 3, but the upper portion of the wick-holder is surrounded, as clearly shown by such figure, and also by

broken lines, Fig. 2, (and see also the left-hand corner of the top of the wick-holder which is shown in section by Fig. 1), with a structure b' of trumpet-shaped section of 5 which the upper edge comes up against, or near to, the under surface of the hood, and upon which, or upon the wick itself, such surface rests. Each side of the hood is formed with a downward flange g' and at 10 the outer face of one of these flanges is marked a scale, and a pointer H which is rigid with the wick-holder, travels along the scale, as the wick-holder turns, and indicates the height at any moment of the oil 15 within the reservoir. At one end of the scale may be marked the letter F indicating "full" and at the other end the letter E indicating "empty."

The hood G is shown to be pivoted to a 20 support K and may be turned back clear of the wick when the same is to be trimmed.

The whole of the burner apparatus may be carried upon a removable dish M which rests upon the top of the reservoir and is 25 kept in place by a surrounding flange a . The wick-holder is surrounded by a shield b^2 which prevents foreign substances from falling through the opening in the top of the reservoir through which the wick-holder 30 passes and within which it tilts.

Plates such as A^1 , spaced apart sufficiently to allow the wick-holder and wick to operate and the oil to flow between them, may be fixed within the reservoir to prevent inconvenient wash when the lamp is being carried.

Referring now to the modification of the invention shown by Fig. 4:—The hood is divided into two parts G^1 which leave a gap 40 g' between them which corresponds to the opening g before described. These hood parts are pivotally connected with supports K^1 upon which they may be turned back clear of the wick. One of the parts is 45 shown by broken lines as partially turned back.

Having fully described my invention, what I claim and desire to secure by Letters Patent, is:—

50 1. The combination, in an oil lamp, of a hood or flame-controller which has a flame opening therethrough, a wick-holder of flat shape which is considerably wider than said flame opening, a flat-shaped wick which passes through said holder and is also considerably wider than said flame opening, and means whereby said wick-holder may be moved in relation to said hood or flame-

controller to bring different portions of the width of the upper termination of the wick 60 in succession beneath said flame opening, substantially as set forth.

2. The combination, in an oil lamp, of a hood or flame-controller which has a flame opening therethrough, a wick-holder of flat 65 shape which is considerably wider than said flame opening and is pivotally connected with the lamp base, a flat-shaped wick which passes through said holder and is also considerably wider than said flame opening, 70 whereby as the wick-holder is turned about its pivot axis it moves the upper end of the wick beneath the flame opening, bringing different portions of the wick in succession beneath such opening.

75 3. The combination, in an oil lamp, of a hood or flame-controller which has a flame opening therethrough, a wick-holder of flat shape which is considerably wider than said flame opening, a flat-shaped wick which 80 passes through said holder and is also considerably wider than said flame opening, and a float within the reservoir for the oil which, as it falls with the level of the oil, operates the wick-holder and thereby moves 85 the upper end of the wick beneath the flame opening.

4. The combination, in an oil lamp, of a hood or flame-controller which has a flame opening therethrough, a wick-holder which 90 is pivotally connected with the lamp base and passes down into the oil reservoir and a float which is carried by the wick-holder, and as it falls with the level of the oil, turns the wick-holder beneath the flame opening, 95 bringing different portions of the wick in succession beneath such opening.

5. The combination, in an oil lamp, of a hood or flame-controller which has a flame opening therethrough, a wick-holder which 100 is pivotally connected with the lamp base, whereby as the wick-holder is turned about its pivot axis it moves the upper end of the wick beneath the flame opening, a scale which is marked upon the flame-controller, 105 and a pointer which turns with the wick-holder and indicates, along said scale, the height of the oil within the reservoir.

In witness whereof I have hereunto signed my name this 19th day of July, 1916, in the 110 presence of two subscribing witnesses.

CHARLES EDMUND PALMER.
